UNITED STATES PATENT OFFICE.

HARRY MILTON DALTON, OF CINCINNATI, OHIO.

AUTOMATIC BOLTWORK FOR SAFES.

1,109,666.

Specification of Letters Patent.

Patented Sept. 8, 1914.

Application filed March 4, 1908. Serial No. 419,218.

To all whom it may concern:

Be it known that I, HARRY M. DALTON, a citizen of the United States, residing at Cincinnati, in the county of Hamilton and State of Ohio, have invented certain new and useful Improvements in Automatic Boltwork for Safes; and I do hereby declare the following to be a full, clear, and exact description of the invention, such as will enable others skilled in the art to which it appertains to make and use the same.

My present invention relates to automatic bolt work for safes to be used in connection with time locks, and has for its object to provide a simple and effective construction that will occupy but a small space.

It also has for its object to provide a construction in which the devices to be actuated by the time mechanism to release the bolt work when the safe is to be opened, shall be locked against all movement from the time of locking the safe until moved by the time mechanism.

In the accompanying drawings I have illustrated two forms in which I have embodied my invention and my said invention is disclosed in the following description and claims.

In the drawings; Figure 1 is a plan view of a time lock comprising three time mechanisms combined with my improved bolt work and connecting means, the dial of one of the time mechanisms being removed. Fig. 2 is a side elevation of the time mechanism and bolt work with the inclosing casing shown in dotted lines. Fig. 3 is a view of my improved bolt work with the top plate removed. Fig. 4 is a top or plan view of the bottom or base plate upon which the other parts are mounted. Fig. 5 is a sectional view on line $x-x$ Fig. 4. Fig. 6 is a top view of the spring carrying plate and the hub of the bolt actuating lever. Fig. 7 is a view of the under side of such plate and lever. Fig. 8 is a sectional view on line $Y-Y$ Fig. 6. Fig. 9 is an isometric perspective of the devices by which the time mechanism controls the detent levers for holding and releasing the bolt work. Fig. 10 is a partial section of the sleeve and its disks forming part of the devices shown in Fig. 9. Figs. 11 and 12 show a modified construction for holding and actuating the time lock trip. Figs. 13 and 14 are views of another form of such construction. Fig. 15 shows an arrangement of three timers with a modified

tripping mechanism. Fig. 16 is a view of the same devices with a section on line $Z-Z$, Fig. 15.

My improved bolt actuating mechanism together with the timers for controlling the same are mounted on a base plate. The base plate A, see Figs. 4 and 5, is provided with two upwardly extending annular walls a, a' the outer of which a forms the side walls of a casing inclosing the bolt operating mechanism. Centrally within the inner wall a' a gudgeon a^2 is provided on the base plate and upon this is mounted the bolt actuating lever B', see Fig. 7. This lever has a hub b and on its upper side is provided with two pins $b' b'$ which engage openings in the bolts B, B, see Fig. 3. The parts B, B as shown are movable parts designed to be connected with and move the actual locking bolts. As they move with the locking bolts for the convenience of description they are herein termed bolts. The openings in the bolts are of such a size and form as to permit the movement of the pins in their curved path around the gudgeon a^2 to effect the straight line movements of the bolts. The bolts B, B are formed as shown with the enlarged outer ends. The heads are enlarged upon one side forming a shoulder b^2 and these heads rest upon blocks A', A' having on each side of the heads of the bolts, guiding projections $a^3 a^3$.

The upper edge of the annular wall a' is cut away to receive the main body of the bolts which lie side by side with the opposite end of one in line with the shoulder b^2 of the other. The bolts are made of such a length that when retracted by the appropriate spring the shoulder b^2 of one will come in contact with the opposite end of the other as shown in dotted lines in Fig. 3 and thus the inward movements of the two will be arrested without shock or jar to the actuating devices.

A plate C is journaled on the upper end of the hub b of the lever B', as shown in Fig. 8, and is provided with an arm c rigidly secured thereto by which it can be turned when desired. This arm extends outwardly beyond the walls a, a' , which walls are cut away to admit the passage of the arm and permit of its being moved. To the underside of the plate C, are secured brackets or clips c', c^2 (see Fig. 7) and in these clips is mounted the rod C' bent into the form of a circle. This rod C' passes freely through

the outer end of the lever B' and through abutment a^4 secured to the base plate. A coiled spring D surrounding the rod C' extends between the lever B' and the clip c^2 and another like spring D' extends between the clip c' and the abutment a^4 as shown in Fig. 7; the abutment a^4 being shown in dotted lines in its relative position when the bolts are in their unlocked position.

10 On the upper side of the plate C is a pin c^4 . When the plate C is turned by its arm c to compress the springs D and D', this pin engages a semi-circular recess or notch in a 15 detent lever E pivoted upon a stud, secured to the base plate A. This lever is provided with a pin e that engages a slot in the secondary detent lever E' and this secondary detent lever is provided with the pin e' to be engaged by the trigger of the time mechanism.

When the parts are assembled for operative action, on turning the plate C by moving its arm c toward the right and to the position shown in Fig. 3, the clips c' c^2 and rod C' will move with it. The lever B' being held from movement by the dogging of the bolts, the spring D will be compressed between the clip c^2 and the lever and the spring D' will be compressed between the 30 clip c' and the abutment a^4 . The pin c^4 will engage the recess in the detent lever E, turning it upon its pivot and causing its pin e to turn the lever E' until the pin e' is engaged and held by the trigger of the time mechanism. If the door of the safe be now closed the dogging devices will release the bolts and the spring D will expand and force the bolts outward to lock the safe. The lever B' will then move toward and engage the clip 35 c' , which holds the spring D' compressed through the detent levers E, E'. These detent levers hold the plate C from turning.

When the detent levers are released by the trigger of the time mechanism and spring 40 D' forces them to release the pin c^4 and the plate C moves back to its unlocked position the clip c' engaging the lever B' and moving it to retract the bolts.

The plate C is provided with the spring 45 detent or pawl that when the bolts are moved to locked position, falls into a notch in one of the bolts and as long as the timer holds the plate C, this pawl holds the bolts from being moved to unlock the safe by any others than the bolt work springs.

The time mechanism is mounted upon a plate C² that is placed upon the annular wall a , and is secured in this position in any preferred manner.

50 In the drawings (see Figs. 2 and 9) I have shown three time movements and so arrange the devices connecting them with the trigger that they may act together to effect this movement should the others fail to act.

65 On each of the winding arbors of the time

movements is placed a disk G having the tooth g . F, F', F² are the tripping arms or levers of the several time movements. Each of these trip levers is pivoted intermediate its ends as at f. The upper ends of these 70 levers are each provided with a centrally extending portion f', the upper edge of which is made concave to closely fit the periphery of the disk G, and on either side of such projection is a notch or recess f² to receive the 75 tooth of the disk G.

When the timers are wound the concavity of the part f' engages the plain portion of the disk G. As the timer is actuated, the disk G moves in a direction the reverse of 80 that in which it moves in winding until the tooth g engages the notch or recess f² when the trip lever is moved. Opposite the central time movement is a stud H, secured to the plate C² upon which is movably mounted the disk h, having the pin h'. The lower end of the trip lever F' lies in close relation to the said pin h' and at the right thereof. To the lower end of the trip lever F² is pivoted the bar f³. The free end of this bar is provided with a slot which engages the pin h' and the bar is so placed that the end of the slot nearest the arm F² is in close relation to the pin. To the lower end of the trip lever F is pivoted a like bar f⁴ having also a slot at its 90 free end engaging pin h' and having the end of the slot farthest from the lever F in like close relation to the pin h'. 95

The disks G when moved by their respective time mechanism, move in the direction of the arrow over each. When, therefore, the tooth g turns its trip lever the lower end of such lever moves to the left and turns the sleeve H' upon its stud.

The lower end of the sleeve H' is provided with two disks h² h³. The lower disk h² is provided with the pin h⁴ and the upper disk h³ with the notch or recess h⁵.

I is the trigger provided with the shoulder i which engages the pin e' of the secondary detent lever which extends upward through the plate C² for the purpose. When thus engaged the bolt work is held in locked position as before explained.

The trigger I is pivoted intermediate its ends and its upper end has a projection i' which is provided with a concave surface to engage the periphery of the disk h³. It is also provided with a notch or recess i² that when the sleeve H is turned engages the pin h⁴ and enables the sleeve to move the trigger to release the pin e' and the detent levers.

The sleeve H' is hollowed out at the base and in this space I locate a spring H² having one end connected to the plate C² and the other to the sleeve H', tending at all times to turn the sleeve to bring the pin h' against the trip lever F' and to the right hand of the slots in the bars f³ and f⁴. 130

When the sleeve H' is turned by the trip levers to move the upper end of the trigger to the right and its lower end to the left to release the pin e' , the pin moves downward along the face i^3 of the trigger which is of such length that the pin will not move below it. The pin e' , therefore, holds the trigger and sleeve H' from being returned to locked position, until the pin e' is raised above the level of the shoulder i , when the spring H^2 will cause the sleeve H' to return to the position shown in Fig. 9, turning the trigger to bring the shoulder i beneath the pin e' and cause a plain portion of the periphery of the disk h^3 to engage the concave surface of the part i' of the trigger. The parts will then be in proper position for locking the safe.

It will be seen in the construction which has been just described, that the trip levers are held against possible movement by reason of jar caused by hammering upon the safe or by the use of an explosive. It will also be seen that the trigger is likewise held from movement unless moved by the timers. Hence the trigger and bolt work are securely locked until released by the time mechanism. The trip levers may also be held and moved at the proper time by constructions shown in Figs. 11 to 14 inclusive. In this form of my invention the trip levers F^x are each provided with a pin F^3 and the disks G' are each provided with a groove g' upon its underside with which the pin F^3 engages. The pin is set at an angle to a line passing longitudinally of the trip lever through its pivot, and when the disk G' is turned so that the pin is engaged by the angular portion of the groove, the lever is turned and the free end of the same will move the sleeve H' as hereinbefore described.

The trip levers F^x naturally assume much the position shown in these figures. The disposition of the weight of the levers being such that there is a tendency for the lever to turn a short distance to bring the pin against the inner wall of the groove. By reason of this fact the disk may be constructed as shown in Figs. 13 and 14, having its outer edges rabbeted away except the portion g^2 , Fig. 13, which acts to force the pin inward. In this case the trip levers could be moved by jar to cause the lower end of the trip levers to swing to the right moving the pin away from the disk G' . But this would not cause any results as such a movement of the trip levers would not release the trigger, and their return movement would put the pins F^3 in their normal position. In Figs. 15 and 16 I have shown this grooved disk as employed in connection with a different form of trigger and with different devices between the disks and the trigger. In this construction the pin f^3

is mounted upon a slide F^4 which is provided with a slot through which the winding arbor of the timer passes and the disk G' is reversed in position so that the slide when its pin f^3 engages with the angular portion of its groove, will move downward instead of upward. Under the lower end of the slide F^4 of the central timer is a stud T and to the top of this stud is pivoted the left end of a bar or lever K . The opposite end of this bar or lever is pivoted to the slide F^4 of the timer at the right. Another bar K' is pivoted to the lower end of the slides of the other two timers. The trigger is an arm K^3 depending from a bar K^2 , the outer ends of which bar are pivoted to bars K , K' near their respective centers.

To the lower end of the arm K^3 is the pivoted block k^2 having the point k^3 projecting beyond the arm and forming a shoulder. k^4 This block is provided further with the shoulder k^4 shown in dotted lines, which engages a pin k^5 to hold the point from turning downward beyond a certain point but permits it to turn upward to allow the pin e' of the secondary detent lever to pass after which it will return to the normal position shown in Fig. 15 and hold the detent lever and bolt work in locked position.

Should all of the timers act the two at the left will draw the bar K' upward while the timer at the right will force the outer end of the bar K downward tilting the arm K^3 to the left and moving the point k^3 from under the pin e' of the detent mechanism thereby releasing the detent levers and permitting the bolts of the safe to be withdrawn. Should the timer to the right only operate the same result is produced as the bar K will turn on the pivot connecting it with the stud T and thus effect the tilting of the arm K^3 . Should the center timer alone act its slide would draw the inner end of the bar K' upward which would also tilt the arm K^3 ; should the timer at the left only act, the same result would be obtained. It will also be seen that no jar from hammering or the use of explosives that does not destroy the lock will through slide F^4 free the detent mechanism and permit the unlocking of the safe.

About the timers and connected parts is placed an inclosing casing L best seen in Fig. 1 and in dotted lines, Fig. 2, and this casing is provided with a hinged glass cover L' partially shown in Fig. 1 as forming a part of the casing L . The casing L has apertures below the plate C^2 through which the bolts B pass. The casing forms above the plate C^2 a perfectly dust proof compartment for the timers and the parts moved thereby.

What I claim and desire to secure by Letters Patent is:—

1. In a safe locking mechanism, the com- 130

- bination with safe bolts, of a spring for moving said bolts from locked to unlocked position, a trigger for holding said spring from movement, a revolute device having a disk for holding said trigger, said trigger being constructed to engage a sufficient extent of the periphery of said disk to be held thereby from movement, a timer mechanism and connecting means to release said trigger.
5. In a safe locking mechanism, the combination with safe bolts, of a spring for moving said bolts from locked to unlocked position, a trigger and connections to hold said spring and bolts in locked position, a revolute device having a disk to hold the trigger from moving from locked position, said disk having a notch in its periphery to release the said trigger to unlock said spring and bolts, and a timer mechanism to move the said disk to unlock the safe.
10. 2. In a safe locking mechanism, the combination with safe bolts, of a spring for moving said bolts from locked to unlocked position, a trigger and connections to hold said spring and bolts in locked position, a revolute device having a disk to hold the trigger from moving from locked position, said disk having a notch in its periphery to release the said trigger to unlock said spring and bolts, and a timer mechanism to move the said disk to unlock the safe.
15. 3. In a safe locking mechanism, the combination with a locking member, of a spring for moving said locking member from locking to unlocking position, means for compressing said spring and moving said locking member to locking position, means including a revolute device for holding the said spring and locking member from movement, said revolute device having a spring connected therewith to move it to and hold it in locking position, and a timer mechanism to move said revolute device to release said bolt spring.
20. 4. In a safe locking mechanism, the combination with a locking member, of a spring for moving said locking member from locked to unlocked position, a trigger operatively connected to said spring to hold said unlocking spring from movement, a revolute device for engaging a recess in said trigger to hold it from movement, a spring for moving said revolute device to and hold it in locking engagement with said trigger, and a timer mechanism to turn said revolute device to release said trigger.
25. 5. In a safe lock, the combination with the safe bolts and a spring for moving them from locked to unlocked position, of a trigger for holding said means from action, said trigger being provided with a concave surface, and a notch or recess adjacent thereto, a trigger holding means having a convex surface for engaging the concave surface of the trigger and a pin or projection adapted to be moved into the notch in the trigger, substantially as described.
30. 6. In a safe locking mechanism, the combination with the safe bolts, of means for moving said bolts from locked to unlocked position, a trigger and connections for holding said unlocking means from action, tripping mechanism for releasing said trigger, a timer mechanism, a disk connected with said timer mechanism for operation thereby, said disk having a portion of its periphery adapted to engage the tripping mechanism and hold it positively from movement and having also a notch in its periphery to actuate the trip to release said trigger.
35. 7. In a safe lock, the combination with the safe bolts, of a spring for moving the bolts from locked to unlocked position, of a trigger for holding said spring from action, a time mechanism having a tripping mechanism, a movably mounted sleeve having a crank pin to be moved by the tripping device of the time mechanism, said sleeve also being provided with means for actuating the trigger to release said spring, substantially as described.
40. 8. In a safe lock, the combination with the safe bolts, of a spring for moving the bolts from locked to unlocked position, a trigger for holding such spring from action, a time mechanism having tripping devices, a movably mounted sleeve provided with a crank pin to be actuated by said tripping devices, and provided also with means for moving said trigger to release the said spring, the construction of said tripping devices and their connections with said trigger being for the purpose of holding the said trigger positively in one position until actuated by the said tripping mechanism.
45. 9. In a safe lock, the combination with the safe bolts, and a spring for moving them from locked to unlocked position, of a trigger operatively connected with said spring and connections for holding said spring from action, a plurality of time movements, a movably mounted sleeve having a crank pin, said sleeve engaging said trigger and holding it from movement when the bolts are in locked position and means whereby one or more of said time movements may engage said crank pin and release said trigger, substantially as described.
50. 10. In a safe lock, the combination with the safe bolts, of a lever connected with said bolts to move them into and out of locked position, a plate having a movement concentric with said lever, a spring carried by said plate for moving said lever in one direction and a spring for moving said plate and lever in the opposite direction, substantially as described.
55. 11. In a safe lock, the combination with the safe bolts, of a lever for moving the bolts into locked and unlocked position, a plate carrying two springs and movable concentrically with the movement of said lever, one of said springs connected with said lever to move it in one direction, and the other connected with said plate to move the same together with the lever in the opposite direction, substantially as described.
60. 12. In a safe lock, the combination with the safe bolts, of a lever for moving the bolts to and from locked position, a plate movable concentrically with the said lever,

5 said plate having upon one side of the same a rod in form of a circle secured thereto, two coiled springs upon said rod, one of said springs being interposed between the said lever and a block on said plate and the other interposed between a block on said plate and an abutment secured to a stationary part of the lock, substantially as described.

10 13. In a safe lock, the combination with the safe bolts, of a lever for moving the bolts to and from locked position, a plate movable concentrically with said lever, a rod in form of a circle secured to one side of said plate, two coiled springs on said rod, one of said springs interposed between a block on said plate and lever and the other interposed between a block on said plate and an abutment secured to a stationary part of the lock, and an arm for moving said plate 15 to compress said springs, substantially as described.

20 14. In a safe lock, the combination with two bolts moving in opposite directions, of a spring for moving said bolts from locked to unlocked position, the main bodies of said bolts lying in close proximity, and each having a head extending on one side past the opposite end of the other bolt, whereby in unlocking the head of one will come in contact with the opposite end of the other and relieve the other parts from shock or strain, substantially as described.

25 15. In a safe lock, the combination with bolts of a lever for moving the same, a plate moving concentrically with said lever, springs for moving said bolts, an arm connected with said plate for compressing said springs, said plate being provided with a pawl or detent to engage a notch in one of 30 said bolts when said bolts are in locked position to prevent the accidental movement of said bolts when in locked position, substantially as described.

35 16. In a safe lock, the combination with the safe bolts, of springs for moving them to and from locked position, a trigger for holding the bolts in locked position, a time mechanism, a revoluble device between the timer and the trigger for the purpose of 40 locking the trigger positively from movement, a spring connected to said revoluble device and tending to move said revoluble device in a direction to lock said trigger, and connections between the revoluble device and the timer to enable the timer to 45 release said trigger, substantially as described.

45 17. In a lock, a movable locking member, a rotatable member, two springs, means for compressing said springs by turning said rotatable member, means operated by one of 50 said springs for moving the locking member to locking position, means operated by the other of said springs for moving the 55 locking member to unlocking position and a

detent device mounted on said rotatable member, the movement of the rotatable member to compress said springs carrying said detent device into position for positively holding the locking member in locking position, 60 substantially as set forth.

18. In a lock, a movable locking member, a plurality of time mechanisms for holding the same in locking position and releasing it at a predetermined time, and connections 65 between said mechanisms and member including a lever pivotally mounted adjacent to each of said mechanisms, a part operated by each mechanism adapted to engage the lever corresponding thereto and rock the 70 same, a latch, and connections between all of said levers and said latch, each of said levers being held against movement except when the time mechanism corresponding thereto is in a definite position, substantially 75 as set forth.

19. In a safe locking mechanism, the combination with a movable locking member, of a spring for moving the said locking member from locking to unlocking position, a trigger operatively connected with said spring to hold said unlocking spring from movement; a revoluble device having a disk at one end to engage a recess in said trigger to hold it from moving, a spring to move 80 said revoluble device to locking position, said revoluble device having also a crank pin, and a timer mechanism to engage said crank pin and turn said revoluble device to 85 release said trigger.

20. In a safe locking mechanism, the combination with the safe bolts, of means for moving said bolts from locked to unlocked position, a trigger for holding the unlocking means from action, a tripping mechanism 90 for said trigger, a timer for actuating said tripping mechanism, means for holding said tripping mechanism positively in one position until actuated by the timer, and means for holding the trigger positively in one position until actuated by the tripping mechanism, substantially as described.

100 21. In a safe locking mechanism, the combination with the safe bolts, of a spring for moving said bolts from locked to unlocked position, a trigger for holding said spring from moving said bolts, a timer mechanism, a lever adapted to be operated by said timer to trip said trigger, said lever being connected with said timer by connecting parts 105 for the purpose of holding the same positively from movement until actuated by the timer.

110 22. In a safe locking mechanism, the combination with the safe bolts, of means for moving said bolts from locked to unlocked position, a trigger for holding said unlocking means from movement, a timer mechanism, tripping devices adapted to be operated by said timer to release said trigger 115 120 125 130

and means for the purpose of holding said tripping devices positively in one position until actuated by said timer mechanism.

23. In a lock, a locking member, a device controlling the position thereof, a plurality of time mechanisms, a member connected to and operated by each of said mechanisms, and levers connected to said device each co-acting at one end with one of said members and adapted to form a positive connection

precluding movement of said device except when one of the time mechanisms is in a predetermined position, substantially as set forth.

In testimony whereof I affix my signature, 15
in the presence of two witnesses.
